UNITED STATES PATENT OFFICE.

HARRY PHIDIAS FORTÉ, OF CANAJOHARIE, NEW YORK, ASSIGNOR TO BEECHNUT
PACKING COMPANY, OF CANAJOHARIE, NEW YORK, A CORPORATION OF NEW YORK.

CAPPING-MACHINE.

1,172,447.

Specification of Letters Patent. Patented Feb. 22, 1916.

Application filed December 4, 1913. Serial No. 804,668.

To all whom it may concern:

Be it known that I, HARRY P. FORTÉ, of Canajoharie, in the county of Montgomery and State of New York, have invented certain new and useful Improvements in Capping-Machines; and I do hereby declare the following to be a full, clear, and exact description of the same, reference being had to the accompanying drawings, forming a part of this specification, and to the reference numerals marked thereon.

My present invention has for its object to provide a machine for affixing or applying caps to bottles, or similar receptacles, and it is intended more particularly to provide an apparatus for screwing onto the necks of bottles, jars or other containers, screw threaded caps and as a type of such receptacles reference is made to the well known catsup bottles.

Generally stated, my invention comprehends the transporting or carrying of a bottle, or receptacle, on which a cap has been previously placed into juxtaposition with a frictional surface which upon being engaged by the cap will effect a relative movement between it and its receptacle whereby the cap is caused to be twisted on its screw thread until it becomes seated in the desired position.

To these and other ends the invention consists in certain improvements and combinations of parts, all as will be hereinafter more fully described, the novel features being pointed out in the claims at the end of the specification.

In the drawings: Figure 1 is an end elevation showing a machine illustrating one embodiment of my present invention; Fig. 2 is a top plan view thereof; Fig. 3 is a horizontal sectional view taken on the line 3^x-3^x of Fig. 1; Fig. 4 is a side elevation, and Fig. 5 is a detail view showing the mounting of the cap-rotating rollers.

Similar reference numerals throughout the several figures indicate the same parts.

In illustrating my present invention I have shown a machine adapted particularly for applying screw caps to bottles, and the particular style of bottle shown is that employed as a container for catsup, but it will be understood at the outset that hereinafter when the term "bottle" is used that it is merely employed as a convenient designation for a receptacle or container irrespective of

its size, shape, or the purpose for which it is intended to be used. The caps applied to the bottles may be of the usual stamped sheet metal form or any preferred construction, being provided internally with screw thread projections coöoperating with lugs or screw threads preferably molded on the exterior of the bottle neck.

A machine embodying my invention, broadly considered, comprises as one element means for transporting a bottle and as a second element means frictionally engaging the bottle cap during said transporting movement and causing it to be revolved upon the bottle so that by the action of the screw threads on the bottle and cap, the latter will be advanced the desired distance and securely seated. This friction surface may be movable and the bottle held against rotation during transportation, or said surface may be stationary and the bottle rotated while it is being carried from one place to another. In the preferred arrangement of the parts I prefer to hold the bottle against rotary movement and to arrange the frictional cap rotating means so that it will engage opposite sides of the cap and apply the pressure, which it is necessary to exert in order to firmly grip the cap, on opposite sides of the latter, thus automatically serving to center the cap on the bottle neck and to quickly and easily rotate it into the desired position thereon.

Referring now to the illustrations, it will be seen that the machine comprises a main frame or table A supported on legs or standards a, a, and b, b, the latter being arranged at opposites of the center of the table and extending vertically and carrying at their upper ends a top frame B. The table A serves as a support for a portion of the conveying devices and on the frame B is mounted the cap rotating devices and the mechanism by which they are driven. Extending transversely above the table is a conveyer belt 1, of any desired length, driven at one end by a pulley 2 on the shaft 3 carrying a driving pulley 4 to which rotary movement is communicated from any convenient source. The conveyer belt is preferably guided between the vertically extending walls 1^a which prevent any lateral movement of the belt and also serve to prevent bottles resting thereon from becoming displaced either before or after the cap-

ping operation due to vibration of the machine or to the movement of the belt itself. The belt is further supported by an underlying plate 1^b, the latter and the side walls 5 1^a being mounted independently of the table A. Coöoperating with the conveyer both for the purpose of positioning the bottles thereon centrally in respect to the capping mechanism and for the purpose of holding 10 the bottles against rotary movement while the caps are being screwed into position, there is arranged above the conveyer two guides spaced apart sufficiently to permit a bottle to be introduced between them, as 15 shown in Fig. 3, and in order to securely hold the bottle without retarding its progress, these guiding surfaces are made in the form of endless belts 5 and 6 which are carried respectively on the pairs of pulleys 20 5^a—5^b, 6^a—6^b, rotating on vertical axes as shown, the bearing studs for one of the pulleys of each pair, such as 5^a and 6^a, being adjustable to vary the tension of the belts. This may be accomplished by means of 25 swinging supports 5^c, 6^c which may be clamped in adjusted position by bolts 5^d and 6^d. It is only necessary that a bottle should be gripped momentarily while its cap is being seated and for this reason the pairs of 30 rollers 5^a—6^a and 5^b—6^b are separated so that the inner or adjacent surfaces of the belts 5 and 6 at their forward ends where the bottles enter and at their rear ends, where the bottles are discharged, the space 35 provided is greater than the diameter of the largest portion of the bodies of the bottles. This permits the belts to perform a further function of moving the bottles laterally on the conveyer 1 to center them in respect to 40 the capping mechanism, and after the latter has performed its operation the bottles are released immediately. In order to cause the belts 5 and 6 to firmly engage the bottles they are each backed by an intermediate 45 roller 5^e, 6^e provided with a thick face formed of rubber or other resilient material, as shown in dotted lines in Fig. 3. For the purpose of accommodating bottles having bodies of different diameters, these 50 backing rollers 5^e and 6^e are mounted on studs carried on swinging arms 5^f and 6^f pivoted at one end, as indicated at 5^g, 6^g and adjustably secured at their opposite extremities, as shown by the lock nuts 5^h and 55 6^h.

The parts described above are all carried on the table A, with the exception of the conveyer, and the table is adjustably secured on standards a b by the split clamps 60 A' whereby the mechanism may be raised or lowered as may be required to accommodate bottles or receptacles of varying lengths.

The capping mechanism proper which 65 engages the bottle caps for the purpose of

screwing them down or seating them on the necks of the bottles is shown, in the present embodiment of my invention, as comprising two frictional surfaces arranged in the form of rollers C and D spaced so as to engage opposite sides of a bottle cap and each disposed to rotate in a plane arranged at a slight angle to a horizontal plane and substantially parallel to the convolutions of the engaging screw threads of the cap and 75 bottle neck at opposite sides of the latter. The capping mechanism is all carried on the top frame B, the rollers C and D being respectively mounted on shafts c, d carried in bearings C', D' provided at their upper 80 ends with yokes C², D² pivoted to laterally extending ears of bearing plates C³, D³, mounted at opposite sides of the depending bracket B' to which latter said bearing plates are secured in the angular position 85 shown in Fig. 5 for the purpose of supporting the rollers C, D in the desired position of angular adjustment. The pivotal mounting of the bearing sleeves C', D' permits the rollers carried by them to move toward 90 and from each other under the influence of a spring 7, the tension of which may be adjusted by nut 8 on a bolt 9 to determine the pressure with which the rollers C, D engage the caps. The movement of the rollers 95 toward each other is limited by the adjustable stop bolts c', d' carried on the sleeves C', D' and engaging the sides of the bracket B'.

Rotary motion is imparted to the rollers 100 C and D, in the direction indicated by the arrows in Fig. 3, so that when a bottle cap is engaged between them it will be driven in a direction to advance it along its thread the required distance to seat it on the neck of the bottle with the desired firmness. This is accomplished while a bottle is being transported between said rollers by the combined action of the conveyer 1 and the holding belts 5 and 6. By reason of the fact that the roller D at the point where its surface engages a bottle cap, is moving in the direction of the conveyer 1 it is desirable that this roll be driven at a slightly increased rate of travel in comparison with 110 the speed of rotation of the roller C. The cap rotating rollers C and D are driven by the pinion C⁴, D⁴ mounted on short shafts, journaled in a frame B which are connected with their respective shafts c and d by universal joints, one of which is shown in Fig. 5 and indicated by C⁵. The driving gears by which the pinions last mentioned are rotated are indicated by 9, 10 and 11, the latter engaging the pinion 12 on the gear 10 and being mounted on the shaft 13. The latter extends downwardly through the hub of the pulley 6^b and through the table A where a pair of beveled pinions 14 connect said shaft to the countershaft 15, carried in 120 125 130

bearings on the lower face of the table A. Another pair of bevel gears 14^a transmit rotary movement from the shaft 15 to the shaft 14^b which drives the pulley 5^c. The 5 countershaft 15 is driven from the shaft 3 by the sprocket chain 16 carried on the sprocket wheels 17 and 18.

The frame B and the cap seating mechanism carried thereon is adjustable vertically 10 to position the capping rollers C and D relatively to the face of the conveyer 1 as may be required for bottles of different heights. This adjustability of the parts may be accomplished in any desired manner, and in the drawings I have shown the 15 frame B provided with the split clamps B² adjustably engaging the standards b, b, and on account of the weight of the frame and the desirability of accuracy in adjusting it 20 vertically I provide on each of the standards, between the clamps B² and stationary collars b', rotatable collars b², the engaging ends of which are provided with inclined cam surfaces whereby when one collar is rotated on the other they will be separated and the frame B elevated.

In the operation of the machine the bottles, or receptacles, after being filled and sealed have their caps placed loosely on the 30 bottle necks, after which they are delivered, by hand or otherwise, to the conveyer belt 1. The bottles are received on the conveyer spaced apart a short distance, and as the conveyer is moving continuously each bottle 35 is in turn brought into the opening between the entrance ends of the belts 5 and 6 and by one or the other of these each bottle is adjusted laterally into central position and is soon firmly gripped between said belts and 40 held against rotation during its travel in a lineal direction covering a space of several inches. While a bottle is thus held it is being transported and its cap engages and forces apart the rollers C and D. These 45 rollers are traveling at differential speeds, but at such speeds relatively to the movement which is being imparted to the bottle itself that during the brief period in which said rollers are permitted to engage the cap 50 the latter is driven the required number of revolutions, or partial revolutions, as the case may be, and caused to be firmly seated on the bottle.

The capping mechanism embodying my 55 invention consists of few parts which are simple in their arrangement and construction and capable of capping large quantities of bottles. The adjustability of the table to carry the guiding and holding members 60 toward or from the conveyer permits bottles having long or short bodies to be operated upon and the independent adjustment of the capping rollers provides for the further accommodation of bottles having long 65 or short necks. Various modifications of

the structure I have shown as a practical embodiment of my invention may be made without departing from the spirit of the invention as defined in the appended claims.

I claim as my invention:

1. In a capping machine, the combination with means for supporting a receptacle with its cap placed thereon, of two surfaces having a relative movement in opposite directions and arranged to engage the cap and 75 impart a rotary movement thereto.

2. In a capping machine, the combination with means for transporting a receptacle to which a cap has been applied and means for holding it against rotation, of a continuously movable surface located at one side of the receptacle and adapted to engage the side of a cap and to rotate it upon the receptacle.

3. A capping machine comprising means 85 for transporting and holding a receptacle and a surface adapted to frictionally engage a cap placed on the receptacle, one of said elements being movable relatively to the other so that the receptacle and surface pass 90 each other and cause a rotary movement of the cap on the receptacle during the transporting of the latter.

4. A capping machine comprising means 95 for transporting a receptacle, a surface located at one side of the receptacle and adapted to frictionally engage the side of a cap carried by the receptacle and into engagement with which said cap is carried during the transporting movement, one of 100 said elements being movable relatively to cause the receptacle and frictional surface to pass each other and rotate the cap on the receptacle.

5. A bottle capping machine comprising 105 means for transporting bottles and a surface located at one side of the receptacle into engagement with which caps placed on the bottles are carried during their transporting movement, said surface and transporting means having a further movement relatively one to the other and serving to effect a relative rotary movement between the bottles and their caps.

6. A machine for twisting screw caps 115 upon receptacles to which they have been loosely applied, comprising means for holding the receptacles against rotation, a device for imparting a rotary movement to the caps and means for causing movement of 120 the holding means in one direction and driving the contacting portion of the cap rotating device in opposite direction.

7. A machine for twisting screw caps 125 upon receptacles to which they have been loosely applied, comprising means for holding the receptacles against rotation and means for transporting them in one direction, a device with which the caps are brought into contact for imparting a rotary 130

movement to them, said cap rotating device being driven to move its cap engaging portion in the direction of the transporting movement and at an increased rate of travel 6 relatively to the speed of movement of said transporting means.

8. A machine for twisting screw caps upon receptacles upon which they have been loosely applied comprising means for transporting the receptacles in approximately a straight line and a surface with which said caps are brought into frictional contact traveling in a direction and at a rate of speed relatively to that of the transporting devices which causes said caps to be rotated into sealing position on their receptacles.

9. A machine for twisting screw caps upon receptacles upon which they have been loosely applied comprising means for transporting the receptacles in an upright position in spaced relation to each other, and a moving surface disposed at one side of the path of movement of the receptacle to engage successively the periphery of each cap and adapted to impart a rotary movement thereto.

10. A machine for twisting screw caps upon receptacles upon which they have been loosely applied comprising two surfaces traveling in opposite directions and transporting devices for carrying a receptacle toward and from said surfaces in position to cause its cap to frictionally engage them.

35 11. A machine for twisting screw caps upon receptacles upon which they have been loosely applied comprising two spaced surfaces traveling in opposite directions and means for successively carrying receptacles 40 with their caps applied between and into frictional contact with said surfaces.

45 12. A machine for twisting screw caps upon receptacles upon which they have been loosely applied comprising two spaced surfaces traveling in opposite directions, means for successively carrying receptacles with their caps applied between and into frictional contact with said surfaces and means for holding the receptacles against rotation 50 during the period of contact of their caps with said surfaces.

55 13. A machine for twisting screw caps upon receptacles comprising a traveling surface, means for transporting the receptacles toward the surface to cause the lateral edges of their caps to frictionally engage and be rotated by the surface and means for engaging and holding the receptacles against rotation during the rotation of the cap without 60 impeding its transporting movement.

14. In a capping machine, the combination with a receptacle conveyer and means moving with the latter for grasping and holding a receptacle against rotation, of means for rotating a cap placed on the re-

ceptacle during the movement of the receptacle and while held by the grasping means.

15. In a capping machine, the combination with a conveyer adapted to receive receptacles in an upright position and means located above the conveyer engaging opposite sides of a receptacle placed thereon to prevent its rotation, of devices located above said holding means for rotating a cap placed on the receptacle and arranged to engage said cap while the receptacle is held against rotation.

16. In a capping machine, the combination with a movable conveyer, a pair of guides located above the latter, said conveyer being adapted to receive receptacles and carry them into engagement with the guides and the latter being adapted to center the receptacles and prevent them from being rotated during a portion of their transporting movement, of means disposed to frictionally engage the peripheries of caps placed on said receptacles and rotate the caps while the latter are so held and centered.

90 17. A machine, for applying screw threaded caps to receptacles comprising means for holding the latter and a frictional surface arranged to engage the side of a cap and disposed to move in a plane substantially parallel to the convolutions of the screw threads at its points of contact with the cap.

95 18. A machine for applying screw threaded caps to receptacles comprising means for holding the latter and frictional surfaces arranged to engage opposite sides of a cap and each disposed to move in a plane substantially parallel to the convolutions of the screw thread at their points of contact with the cap.

100 19. A machine for applying screw threaded caps to receptacles comprising means for holding the latter and frictional surfaces arranged to engage opposite sides of a cap 110 and moving in opposite directions and disposed in intersecting planes, the angularity of which is adjusted to facilitate the advancing movement imparted to the cap by its screw thread.

115 20. A machine for applying screw threaded caps to receptacles comprising means for moving a receptacle in substantially a straight line direction and frictional surfaces arranged to simultaneously engage opposite sides of a cap and moving in opposite directions at differential speeds.

120 21. A machine for applying screw threaded caps to receptacles comprising means for transporting a receptacle in substantially a straight line direction and rotating frictional members traveling at differential speeds, said members being disposed in intersecting planes and arranged to engage opposite sides of a cap at such angles that 125

- the rotary movement imparted to a cap will be in the direction of its threads at the points of contact.
22. In a capping machine, the combination with a conveyer moving in a fixed horizontal plane, and adapted to transport receptacles, and grasping devices adjustable bodily toward and from the conveyer and adapted to engage the bodies of receptacles to prevent them from being rotated during their transporting movements, of means for affixing caps to the receptacles while being transported, said means being bodily adjustable toward and from the conveyer.
23. A capping mechanism comprising a conveyer, means for affixing caps to receptacles carried by the conveyer and means for holding said receptacles during the affixing operation, said conveyer and affixing means being relatively adjustable to accommodate receptacles of different heights and said holding means being independently adjustable relatively to the conveyer to accommodate receptacles of different diameters.
24. In a capping machine, the combination with a conveyer adapted to receive bottles in an upright position and supported in a fixed horizontal plane, two endless belts spaced apart and located above the conveyer, means supporting said belts and adjustable toward and from the conveyer, of means for affixing caps to bottles transported by the conveyer and supporting devices for said means adapted to be adjusted toward and from said conveyer.
25. In a capping machine, the combination with a frame having uprights, a conveyer supported in a fixed horizontal plane, a table vertically adjustable on the uprights and devices supported thereon and adapted to engage and afford lateral support for receptacles carried on the conveyer, of a top frame also vertically adjustable on the uprights and means depending therefrom for affixing caps to receptacles on the conveyer.
26. In a capping machine, the combination with a conveyer, means coöoperating with the latter for supporting receptacles placed thereon and a frame arranged above said parts, of rollers suspended from said frame and adapted to engage caps carried by said receptacles.
27. In a capping machine, the combination with means for supporting receptacles, and a frame arranged above said supporting means, of rollers yieldingly suspended from said frame and adapted to move toward and from each other and to operate on caps carried by said receptacles.
28. In a capping machine, the combination with means for holding receptacles and a frame arranged above said holding means, of a suspended bearing pivoted on said frame, a roller adapted to engage caps carried by said receptacles and, having a driving shaft journaled in the bearing and mechanism on the frame for driving said shaft.
29. In a capping machine, the combination with means for holding receptacles, of a support located above the holding means, a bearing suspended from the support and pivoted to swing at an angle to a vertical line, a roller journaled on said bearing adapted to engage caps placed on the receptacles, driving mechanism mounted on the support and a universal joint forming a driving connection between said mechanism and roller.
30. In a capping machine, the combination with means for holding a receptacle, a support located above said means and two pivoted bearings suspended from said support and journaled to swing in intersecting planes, inclined relatively to the vertical plane, of rollers adapted to engage with caps placed on the receptacles and journaled on said bearings and means for driving said rollers.
